SAFETY RAZOR AND BLADE

Joaquin Martorell, New York, N. Y.

Application October 19, 1935, Serial No. 45,806

3 Claims. (Cl. 30—56)

This invention relates to an improved safety razor and blade, and the object of the invention is to provide an improved safety razor blade holder, characterized by such a construction and arrangement of parts whereby a cap is omitted and the guard is of such a character that it can be readily adjusted to accommodate blades of different width, and can also retain the blade at the desired curvature thereon.

The invention together with its objects and advantages will be best understood from a study of the following description taken in connection with the accompanying drawing wherein:

Figure 1 is an elevational view of the safety razor.

Figure 2 is an edge elevational view taken at right angles to Figure 1.

Figure 3 is a vertical sectional view.

Figure 4 is a plan view.

Figure 5 is a perspective view of a spring member.

Figure 6 is an elevational view of one of the guard sections.

Figure 7 is an edge elevational view of a guard section.

Figure 8 is a plan view of a blade, and

Figure 9 is a perspective view of one of the handle sections.

Referring to the drawing by reference numerals it will be seen that the improved razor comprises a pair of complementary guard plates 5 and 6 each of which, adjacent one edge and at opposite corners thereof is provided with upwardly extending projections 7 for engaging a blade in a manner clearly shown in Figure 3 for retaining the blade in position thereon.

At their inner or confronting edges the plates 5 and 6 respectively are provided with depending skirt portions 8 and 9 respectively, and integral with the skirt portion 8 of the guard plate 5 is a handle section 10.

Complementary to the handle section 10 is a handle section 11, and the handle sections 10 and 11 at their meeting edges are provided with outstanding marginal flanges 12 and 13 respectively as shown.

Adjacent the upper end thereof the handle section 10 has its flanges extended and reversely bent to provide spring fingers or lugs 14 adapted to engage over the end edges 15 of the flange 13 of handle section 11 as suggested in Figure 2.

Also at the bottom or free end thereof the handle section 10 has its flange 11 provided with an integral lug or finger 16 engaging in a notch 17 in the lower or free end of the handle section

11 as will be clear from a study of Figures 3, 5 and 9. Thus the fingers 14 and 16 thus engaging the handle section 11 in the manner explained serve to releasably secure the handle sections together.

The skirt 9 of the guard plate 6 is provided with a shank or extended portion 18 which extends into the hollow of the handle formed by the sections 10 and 11 and as clearly shown in Figure 3. At the junction of the skirt 9 and extension 18 are shoulders 19 which rest on the adjacent end of the handle section 11 whereby said section forms a fulcrum for the plate 9.

Also accommodated within the handle formed by the sections 10 and 11 is a spring member 20 one end edge of which is clamped between the meeting edges of the handle sections 10 and 11 at the free end of the handle and as shown in Figure 3.

The spring member 20 has a narrow elongated extension 20a which bears against the side of the shank 18 opposite to the handle section 10 in a manner clearly shown in Figure 3 for normally biasing skirt 9 and associated guard plate 6 away from skirt 8 and associated guard plate 5.

An adjusting screw 21 has a non-threaded portion of its shank accommodated within a suitable opening provided in the skirt 8 and said shank of the screw has a threaded portion screw threadedly engaged with a fork 22 provided on the skirt 9. Obviously, through the medium of the screw 21, skirt 9 and associated plate 6 may be readily adjusted relative to skirt 8 and its associated guard plate 5 and as may be required dependent upon whether or not it is desired to support the blade 22 either substantially flatly upon the guard plate or in a transversely curved condition as for example suggested in Figure 3.

To guide the skirt 9 and plate 6 so that the same moves relatively to the skirt 8 and associated plate 5 in a substantially horizontal plane, the skirt 8 at its opposite edges is provided with guide fingers 23 that are accommodated in notches 24 provided in opposite side edges of the skirt 9 and as will be clear from a study of Figures 2, 45 6 and 7.

It will be apparent that the guard plates and their skirts may be stamped from single blanks of material as is also the case with the handle sections, and that accordingly a razor of this character may be cheaply and economically manufactured and consequently retailed for a nominal price.

Having thus described the invention, what is claimed as new is:

1. In a safety razor, a pair of complementary guard plates each provided adjacent one edge and at opposite corners with blade engaging means, said plates at their confronting edges being provided with depending skirts, a handle section integral with one of said skirts, a handle section complementary to the first handle section, inter-engaging means on said handle sections for securing said sections together, and the other of said depending skirts having a shank extending inwardly between the handle sections, and a spring member secured between said handle sections and having an end bearing on said shank and normally biasing the second skirt away from the first named skirt.
2. In a safety razor, a pair of complementary guard plates each provided adjacent one edge and at opposite corners with blade engaging means, said plates at their confronting edges being provided with depending skirts, a handle section integral with one of said skirts, a handle section complementary to the first handle section, inter-engaging means on said handle sections for securing said sections together, and the other of said depending skirts having a shank extending inwardly between the handle sections, and a spring member secured between said handle sections and having an end bearing on said shank and normally biasing the second skirt away from the first named skirt, and an adjusting screw

extending through openings in said skirts having threaded engagement with one of the skirts for adjusting the guard plates and for securing said plates at the desired adjustment.

3. In a safety razor, a pair of complementary guard plates each provided adjacent one edge and at opposite corners with blade engaging means, said plates at their confronting edges being provided with depending skirts, a handle section integral with one of said skirts, a handle section complementary to the first handle section, inter-engaging means on said handle sections for securing said sections together, and the other of said depending skirts having a shank extending inwardly between the handle sections, and a spring member secured between said handle sections and having an end bearing on said shank and normally biasing the second skirt away from the first named skirt, and an adjusting screw extending through openings in said skirts having threaded engagement with one of the skirts for adjusting the guard plates and for securing said plates at the desired adjustment, guide fingers extending from the first one of said skirts, and the second one of said skirts having notches accommodating said guide fingers and cooperable therewith for holding said plates in substantially the same plane to facilitate adjustment of the plates relative to one another.

JOAQUIN MARTORELL. 30
